UNITED STATES PATENT OFFICE.

AINSLEY L. JONES, 2d, OF MARINERS HARBOR, NEW YORK.

BLOCK SYSTEM FOR ELECTRIC-RAILWAY TRAINS.

1,391,322.

Specification of Letters Patent. Patented Sept. 20, 1921.

Application filed January 22, 1921. Serial No. 439,067.

To all whom it may concern:

Be it known that I, AINSLEY L. JONES, 2d, a citizen of the United States and residing at Mariners Harbor, Staten Island, in the 5 county of Richmond and State of New York, have invented certain new and useful Improvements in Block Systems for Electric-Railway Trains, of which the following is a specification, such as will enable those skilled 10 in the art to which it appertains to make and use the same.

This invention relates to block systems for electric railway trains, and particularly to miniature or toy trains of this class, and 15 the object of the invention is to provide in combination with the tracks of a railway system of this class electrical and mechanical means at predetermined points along the tracks of the system for controlling the 20 progress of one or more electric cars or trains movable thereon, in other words, to provide what is commonly known as an automatically operated electrical block system which will operate in the manner of similar 25 block systems on electric transit and other railway systems now in use on numerous railway systems throughout the country, and with this and other objects in view the invention consists in an apparatus of the 30 class and for the purpose specified which is simple in construction and operation, and efficient in use, and which is constructed and operated as hereinafter described and claimed.

35 The invention is fully disclosed in the following specification, of which the accompanying drawings form a part, in which the separate parts of my improvement are designated by suitable reference characters in 40 each of the views, and in which:

Figure 1 is a diagrammatic plan view of one form or model of a railway system diagrammatically illustrating one use of my improved block system in connection therewith;

Fig. 2 a plan view of a part of the track system shown in Fig. 4 on an enlarged scale and showing one of a number of mechanisms which I employ in detail;

50 Fig. 3 a partial section on the line 3—3 of Fig. 2 with part of the construction broken away, and showing only the mechanical construction of the device, the electrical connections being omitted;

55 Fig. 4 a view similar to Fig. 2 with parts

of the construction omitted and parts in section and diagrammatically illustrating the operation of certain parts of the mechanism;

Fig. 5 a partial section on the line 5—5 of Fig. 2 and showing a detail of the construction and the method of its operation;

Fig. 6 a partial section on the line 6—6 of Fig. 5 and on an enlarged scale;

Figs. 7 and 8 are diagrammatic views of two of the mechanisms which I employ in the track system as shown in Fig. 1, and illustrating the different positions said mechanisms assume in the operation of the apparatus; and,

Fig. 9 a view similar to Fig. 1 but showing only a detail of the construction and with parts in a different position.

In Fig. 1 of the drawing I have diagrammatically illustrated one use of my improved block system in which 10 represents an approximately rectangular track construction within which is an approximately elliptical track 11 forming part of the track system 10 through a switch construction shown at 12, said switch construction being composed of two parts or sections 13, controlled by separate switch levers 14 and 15. It will be understood, of course, that my invention is not limited to any specific arrangement of track and the combination 85 illustrates one use of switch sections in a complete system.

All of the tracks in the system shown in Fig. 1 constitute inner and outer side rails 16 and 17 between which is a central or third rail 18 from which electric current, from a suitable source 19, is taken by an electric locomotive or car 20 partially illustrated in Fig. 3 of the drawing, and which carries electric contact rollers, one of which is shown at 21 in said figure. The construction of the track and locomotives or cars forms no part of this invention and said track and cars may be constructed in any desired manner, the above construction being shown for the purpose of clearly illustrating my invention and the method of its use.

In Fig. 1 I have diagrammatically illustrated at 22, 23, 24 and 25 four of my improved signal post constructions co-operating with the track system shown and all of which are constructed in the same manner, and in Fig. 2 of the drawing, I have diagrammatically illustrated the post construction 23 in detail and the method of its con-

nnection with the track system, or one of the sections or parts 26 thereof.

The signal post construction 23, shown in Fig. 2 of the drawing, comprises a suitable base 27 composed of insulating material, and this base is mounted in connection with the track section or part 26 in any desired manner, the rails 17 and 18 being mounted thereon in the construction shown. Mounted upon the base 27 is a semaphore post or standard 28 forming a part of said post construction and at the top of which is pivoted a signal arm 29 carrying red and green translucent panels 30 and 31 adapted to cooperate with an electric lamp or bulb 32 mounted at the upper end portion of the post 28. The bulb 32 is placed in electrical connection with the rails 17 and 18 through circuit wires 33 and 34. The construction of the semaphore and the light bulb also forms no part of this invention, but is merely shown to clearly illustrate the operation of my improved block system.

Pivoted to the base 27 is an approximately triangular plate 35 to one corner portion of which is pivoted a rod 36, which is pivotally connected with the signal arm 29, as clearly shown in Figs. 2 and 3 of the drawing, and pivoted to the other corner portion of said plate is a rod 37 which extends forwardly or in the direction of the rails of the track section 26, downwardly through an aperture 38 in the bottom of the base 27, and forwardly within a cut-out portion 39 of the base and is pivoted to a lever 40 pivotally mounted within the cut-out portion 39 of the base as indicated at 41 in Fig. 3 of the drawing.

I also employ an electro-magnet 42 which is mounted upon the base 27, and an armature arm 43 pivoted at 44 cooperates with said magnet, and one end portion of said arm is connected with the rod 37, as clearly shown in Fig. 2, and connected with the other end of said armature arm is a coil spring 45 the tension of which may be adjusted by a screw 46 mounted in a suitable support 47. The electro-magnet 42 is placed in direct electrical communication with the rail 17 through a circuit wire 48 and is adapted to be placed in electrical communication with the rail 18 through a circuit wire 49 which connects with an automatically operated switch device 50.

The switch device 50 is pivotally or rotatably mounted upon the base 27 and provided with three projecting contact fingers 51, 52 and 53, the finger 53 being insulated from the other two fingers 51 and 52. The switch device 50 is placed in mechanical connection with the lever 40 through a rod 54, as indicated in dotted lines in Fig. 2, and shown in full lines in Figs. 7 and 8, whereby the operation of said switch device will operate said lever and the movement of

the lever will operate said switch device as hereinafter set out.

I also employ in connection with the track system a ground rail 55 which, in the form of construction shown, is preferably located at the inner side of the rail 17 of the track system shown, and said ground rail forms a part of each track section or unit. The ground rails of the separate sections or units are coupled together as illustrated at 56 but the connection between the ground rails is broken as shown at 57, where the signal post constructions are located in the railway system and intermediate of said signal post constructions, said ground rail is continuous or unbroken. The part 58 of the ground rail of the section 26 is placed in electrical connection with the contact finger 53 on the switch device 50 through a circuit wire 59, while the contact finger 51 of said switch device is adapted in one position thereof to cooperate with the other part 60 of said ground rail on the track section 26, this position of the switch device being illustrated in Fig. 7 of the drawing and also indicated in dotted lines in Fig. 4 of the drawing.

As previously stated each of the signal post constructions 22 to 25 inclusive will be constructed in the same manner as the post construction 23 specifically shown and described herein, and the operation of the apparatus in the progress of an electric locomotive or a train on the track system shown in Fig. 1 will be as follows, it being assumed that the locomotive or train is traveling on said track system in the direction of the arrow α in Fig. 1. For the purpose of description it will be assumed that the post construction diagrammatically illustrated in Fig. 7 is the post construction 23, and that shown in Fig. 8 is the post construction 22, and that the locomotive or train has just passed the signal post construction 23, and the operation will be as follows. Prior to the passage of the locomotive or train by the signal post construction 23, or before said locomotive or train reached said post construction, the post construction 22 or the various parts thereof, were in a position similar to that shown in Fig. 7, while the various parts of the post construction shown in Fig. 7, were in a position similar to that shown in Fig. 8, and immediately upon the passage of the signal post construction 23 by a locomotive or train, the switch device 50 is operated or moved into the position shown in Fig. 7 from a position similar to that shown in Fig. 8, by a downwardly directed finger 61 carried by the locomotive or train and which is indicated in Figs. 3 and 4 of the drawing. The operation of the finger 61 is indicated in full and dotted lines in Fig. 4 as is also the movement of the switch device above set out. The result of the above operation will reverse the position of the va-

rious parts of the post constructions 22 and 23 herein specified or will bring them into the positions shown in Figs. 7 and 8 of the drawing, in other words, the signal arm of the post construction 22 which was previously set at danger or in approximately horizontal position will be moved to an inclined position as shown in Fig. 8, and the signal arm 29 of the post construction 23 which was previously in a position similar to that shown in Fig. 8 will be moved into an approximately horizontal position, or at danger as illustrated in Fig. 7.

It will be apparent that as a train or locomotive progresses over the track system, or as it approaches and passes the separate signal post constructions thereon, the above operations will be produced and the mechanical as well as the electrical operations of the separate post constructions will be as follows. The electro-magnet 42 is energized or an electric current is passed therethrough when the parts are in the position shown in Fig. 8, and the armature is moved by said electro-magnet from the position thereof shown in Fig. 7 against the tension of the spring 45, which operation moves the switch device 50 from the position shown in Fig. 7 to that shown in Fig. 8 through the lever 40 and rod 54 and in the position of the parts shown in Fig. 8 the circuit between the ground rail 55, or the part 58 thereof, and the rail 18 is broken as is also the connection of the switch device 50, or the finger piece 51 thereof, with the part 60 of the ground rail as is clearly illustrated in said figure, but when a train or locomotive passes the switch device 50 and moves the same into the position shown in Fig. 7, it will be noted that the circuit is broken through the electro-magnet 42 as illustrated in Fig. 7, and the armature is moved into the position shown in said figure by said switch device through the lever 40 and rods 54 and 37, and the spring 45 aids in this operation. The signal arm 29 of the semaphore is also moved from a position similar to that shown in Fig. 8 to the position shown in Fig. 7 in the above operation, by reason of the mechanical connection of said signal arm with the rod 37 through the rod 36 and triangular plate 35, and this operation is illustrated in dotted lines in Fig. 3 of the drawing.

After the train or locomotive passes a signal post construction and produces the result shown in Fig. 7 of the drawing, the signal post construction previously passed is automatically moved from a position similar to that shown in Fig. 7 to the position shown in Fig. 8, by reason of the completion of the circuit from the third rail 18 through the circuit wire 59 of the post construction 23 to the part 58 of the ground rail 55, through said ground rail backwardly

to the part 60 of the ground rail on the signal post construction 22 through the contact finger 51 which was previously in a position similar to that shown in Fig. 7, through the circuit wire 49 to the electro-magnet thus completing the circuit through the electro-magnet of the signal post construction 22 which will cause said magnet to move the armature arm 43 from a position similar to that shown in Fig. 7, to the position shown in Fig. 8, thus, automatically, the signal arm 29 of the post construction 22 will be moved into the position shown in Fig. 8 upon the movement of the switch device 50 of the post construction 23 into the position shown in Fig. 7. In short, as a train or locomotive passes a signal post construction, the signal arm and various other parts of which are in a position similar to that shown in Fig. 8, said parts are automatically moved into the position shown in Fig. 7, in the manner hereinbefore stated, and at the same time, or in the same operation, a signal post construction previously passed by the locomotive and in which the signal arm thereof and various other parts were in a position similar to that shown in Fig. 7, will be automatically moved into a position similar to that shown in Fig. 8, in the manner hereinbefore set out, thus producing an automatically operated block system for railway apparatus of the class under consideration.

It will be understood that the construction hereinbefore described will constitute a complete operative block system, but in order to make the same more effective in operation and use, I preferably employ in connection with the separate signal post constructions 22 to 25 inclusive, means for automatically stopping a locomotive or train as it approaches the signal arm of one or more of said post constructions set at danger or in a position similar to that shown in Fig. 7, or as illustrated in dotted lines in Fig. 3. This result is accomplished by mounting in connection with each of the signal post constructions a supplemental rail 62 composed of non-conductive or insulating material, and in Figs. 2, 3, 5 and 6 of the drawing this rail is shown in detail in connection with the track section or part 26, which forms a part of the signal post construction 23.

The rail 62 is mounted at one side of the central or third rail 18 and is held in engagement therewith by a plurality of bolts or rivets 63, which pass through elongated apertures 64 in said rail which are arranged at an inclination to the horizontal plane of the rail, as clearly shown in Fig. 5 of the drawing. Connected with the rail 62 approximately centrally thereof is a rod 65 which also connects with the lever 40, as clearly illustrated in Figs. 2 and 4 of the

drawing. The end portion 66 of said rod is bent downwardly and transversely beneath the rail 18 in the construction shown.

The height of the rail 62 when in its normal position is such that the top of said rail is located at a predetermined distance below the top of the central or third rail 18 of the track section 26 as is illustrated in full lines in Figs. 3, 5 and 6 of the drawing, and this is the position said rail assumes when the signal arm 29 of the post construction 23 is in the position shown in full lines in Fig. 3, and when said signal arm is moved into the position indicated in dotted lines in Fig. 3, in the manner herein set out, the operation of the lever 40 from the position shown in Fig. 8 to the position shown in Fig. 7 of the drawing will move the rail 62 into the position indicated in dotted lines in Figs. 5 and 6 of the drawing, in which position the top face of said rail extends above the top face of the rail 18 as shown in full lines in Fig. 7 of the drawing, and the contact rollers 21 carried by the electric locomotive or train 20 as they approach the rail 62 will be raised out of engagement with the rail 18, thus breaking the circuit through the rail 18, and said contact rollers resulting in the automatic stopping of the motor on said locomotive or train. It will also be apparent that when the various parts of a signal post construction are automatically returned into the position shown in Fig. 8 from a position similar to that shown in Fig. 7, as hereinbefore set out, the contact rollers 21 will again be brought into contact with the rail 18 by reason of the movement of the rail 62 into the position shown in Fig. 8, or in full lines in Figs. 5 and 6.

In view of the foregoing it will be apparent that if two locomotives or trains are operating on the track system a collision will be automatically avoided in that one train can not overtake another on the same track or run into a block on such track until said train has passed a block of the system into which the following train is about to enter.

In Figs. 1 and 9 of the drawing, I have also illustrated a mechanical construction co-operating with the switch lever 14 of the switch device 13 for operating two supplemental rails 62 similar in all respects to the rails 62 employed in connection with the separate signal post constructions but which are operated by rods 67 and 68 connected therewith, and with the opposite ends of a lever 69 pivoted to a suitable support at 70, and to one end portion of said lever is connected a rod 71, which is also connected with the switch operating lever 14. With this construction in the operation of the switch lever 14 to open or close the switch 13 thereof, the rails 62 which are operated through the rods 67 and 68 will be moved into such position as to stop a locomotive or train if

it attempts to enter or pass an open or closed switch, or a switch which is not set in the proper position as to permit of the successful passage of the locomotive or train over the track system and through said switch. In other words, if the switch be in the position shown in Fig. 1 the train may pass around the track 10 and through the switch, but if the train be switched into the track 11 by operating the switch lever 15 and said train approaches the part 13 of the switch which is operated through the lever 14, said train will be automatically stopped by the insulating rail 62 unless said switch device has been moved into the position shown in Fig. 9, but if the train is automatically stopped the operation of said switch into the position shown in Fig. 9 will permit the train to proceed without any inconvenience or difficulties whatever. The above operation will be reversed if the locomotive or train attempts to enter the switch as shown in Fig. 9 when the train is progressing on the track 10.

It will be understood that while I have shown numerous details of construction for carrying my invention into effect, and illustrated a specific form and arrangement of track system, I am not necessarily limited to these details, and various changes in and modifications of the construction herein shown and described may be made, within the scope of the appended claims, without departing from the spirit of my invention or sacrificing its advantages.

The automatic locomotive or train stopping mechanism involving the supplemental rail 62 composed of insulating material and the various parts connected therewith is not specifically claimed in this case for the reason that said mechanism may be used independent of the block system, if desired, and said automatic stop mechanism is made the subject of a companion application executed and filed of equal date herewith.

Having fully described my invention, what I claim as new and desire to secure by Letters Patent, is:—

1. An automatically operated block system for miniature electric railways provided with current carrying rails comprising a plurality of signal post constructions located at predetermined points along the track of a railway, said signal post constructions being provided with signal elements, electrical means in said signal post constructions in electric circuit with the current carrying rails of the track for operating said signal elements in one direction, mechanical means in said signal post constructions for operating said signal elements in the opposite direction, means on a locomotive or car adapted to coöperate with the last named means of said signal post constructions for automatically operating the signal elements

thereof in the passage of said locomotive or car by said signal post constructions, and rails coöperating with the means for actuating said signal elements for automatically stopping a locomotive or car approaching a signal post construction, the signal element of which is set at danger.

2. An automatically operated block system for miniature electric railways provided with current carrying rails comprising a plurality of signal post constructions located at predetermined points along the track of a railway, said signal post constructions being provided with signal arms, electro-magnets on said signal post constructions and normally in electric circuit with the current carrying rails of the track, armature arms coöperating with said electro-magnets and in operative connection with said signal arms, said electro-magnets being adapted to operate said signal arms in one direction, mechanical means involving electric switch devices in operative connection with said signal arms and adapted to move said arms in the opposite direction, and means carried by the locomotive or car for automatically actuating said last named means and said switch device in the progress of said locomotive or car on the track and by the separate signal post constructions.

3. An automatically operated block system for miniature electric railways provided with current carrying rails comprising a plurality of signal post constructions located at predetermined points along the track of a railway, said signal post constructions being provided with signal arms, electro-magnets on said signal post constructions and normally in electric circuit with the current carrying rails of the track, armature arms coöperating with said electro-magnets and in operative connection with said signal arms, said electro-magnets being adapted to operate said signal arms in one direction, mechanical means involving electric switch devices in operative connection with said signal arms and adapted to move said arms in the opposite direction, means carried by the locomotive or car for automatically actuating said last named means and said switch device in the progress of said locomotive or car on the track and by the separate signal post constructions, and a ground rail extending longitudinally of the track, said rail being interrupted adjacent to the separate signal post constructions, of said railway and in electric circuit with said switch devices.

4. An automatically operated block system for miniature electric railways provided with current carrying rails comprising a plurality of signal post constructions located at predetermined points along the track of a railway, said signal post constructions be-

ing provided with signal arms, electro-magnets on said signal post constructions and normally in electric circuit with the current carrying rails of the track, armature arms coöperating with said electro-magnets and in operative connection with said signal arms, said electro-magnets being adapted to operate said signal arms in one direction, mechanical means involving electric switch devices in operative connection with said signal arms and adapted to move said arms in the opposite direction, means carried by the locomotive or car for automatically actuating said last named means and said switch device in the progress of said locomotive or car on the track and by the separate signal post constructions, a ground rail extending longitudinally of the track, said rail being interrupted adjacent to the separate signal post constructions of said railway and in electric circuit with said switch devices, and said switch devices being adapted to place said ground rail in electrical communication with one of the current carrying rails of the railway.

5. An automatically operated block system for electric railways provided with current carrying rails comprising a plurality of signal post constructions located at predetermined points along the track of a railway, said signal post constructions being provided with signal arms, electro-magnets on said signal post constructions and normally in electric circuit with the current carrying rails of the track, armature arms coöperating with said electro-magnets and in operative connection with said signal arms, said electro-magnets being adapted to operate said signal arms in one direction, mechanical means involving electric switch devices in operative connection with said signal arms and adapted to move said arms in the opposite direction, means carried by the locomotive or car for automatically actuating said last named means and said switch device in the progress of said locomotive or car on the track and by the separate signal post constructions, a ground rail extending longitudinally of the track, said rail being interrupted adjacent to the separate signal post constructions of said railway and in electric circuit with said switch devices, said switch devices being adapted to place said ground rail in electrical communication with one of the current carrying rails of the railway, supplemental rails composed of insulating material movably mounted in connection with one of the current carrying rails of the railway adjacent to the separate signal post constructions, and means for placing said supplemental rails in mechanical connection with the means for operating said signal arms whereby when the signal arm of one of said signal post constructions is

set at danger the current to the locomotive or car approaching said signal post construction will be broken.

6. The combination with one of the track 65 sections of an electric railway system, said track sections being provided with current carrying rails; of a suitable base, a post mounted in said base and provided with a movable signal arm, an electro-magnet on 70 said base, an armature arm coöoperating with said magnet and in operative connection with said signal arm, a three point switch device movably mounted on the base, a ground rail forming part of said track section, 75 said rail being interrupted at a pre-determined point on said section to divide the same into independent parts, means for placing one of said parts in electrical connection with one of the points of the switch 80 device, the other points thereof being insulated from said last named point, said other two points of said switch device being in electrical communication with said electro-magnet and one of which is adapted to 85 coöperate with the other part of said ground rail while the other of said points is adapted to coöperate with one of the current carrying rails of said track section, and said electro-magnet being placed in electrical communication 90 with the other current carrying rail of said track section.

7. The combination with one of the track sections of an electric railway system, said track sections being provided with current 95 carrying rails; of a suitable base, a post mounted on said base and provided with a movable signal arm, an electro-magnet on said base, an armature arm coöoperating with said magnet and in operative connection 100 with said signal arm, a three point switch device movably mounted on the base, a ground rail forming part of said track section, said rail being interrupted at a predetermined point on said section to divide the same into independent parts, means for placing one of said parts in electrical connection with one of the points of the switch device, the other points thereof being insulated from said last named point, said other two points 105 of said switch device being in electrical communication with said electro-magnet and one of which is adapted to coöperate with the other part of said ground rail while the other of said points is adapted to coöperate 110 with one of the current carrying rails of said track section, said electro-magnet being placed in electrical communication with the other current carrying rail of said track section, said switch device being in operative connection with said signal device, and means carried by a locomotive or car movable over said track section for automatically operating said switch device to move the same in one direction.

8. The combination with one of the track 115 sections of an electric railway system, said track sections being provided with current carrying rails; of a suitable base, a post mounted in said base and provided with a movable signal arm, an electro-magnet on 120 said base, an armature arm coöoperating with said magnet and in operative connection with said signal arm, a three point switch device movably mounted on the base, a ground rail forming part of said track section, said rail being interrupted at a predetermined point on said section to divide the same into independent parts, means for placing one of said parts in electrical connection with one of the points of the switch device, the other points thereof being insulated from said last named point, said other two points of said switch device being in electrical communication with said electro-magnet and one of which is adapted to 125 coöperate with the other part of said ground rail while the other of said points is adapted to coöperate with one of the current carrying rails of said track section, said electro-magnet being placed in electrical communication with the other current carrying rail of said track section, said switch device being in operative connection with said signal device, means carried by a locomotive or car movable over said track section for automatically operating said switch device to move the same in one direction, and means whereby when the circuit is automatically completed through said electro-magnet said switch device will be moved into the opposite direction.

9. The combination with one of the track sections of an electric railway system, said track sections being provided with current carrying rails; of a suitable base, a post mounted in said base and provided with a movable signal arm, an electro-magnet on said base, an armature arm coöoperating with said magnet and in operative connection with said signal arm, a three point switch device movably mounted on the base, a ground rail forming part of said track section, said rail being interrupted at a predetermined point on said section to divide the same into independent parts, means for placing one of said parts in electrical connection with one of the points of the switch device, the other points thereof being insulated from said last named point, said other two points of said switch device being in electrical communication with said electro-magnet and one of which is adapted to coöperate with the other part of said ground rail while the other of said points is adapted to coöperate with one of the current carrying rails of said track section, said electro-magnet being placed in electrical communication with the other current carrying rail of said track section, said switch device being in operative connection with said signal device, and means carried by a locomotive or car movable over said track section for automatically operating said switch device to move the same in one direction.

- switch device being in operative connection with said signal device, means carried by a locomotive or car movable over said track section for automatically operating said 5 switch device to move the same in one direction, means whereby when the circuit is automatically completed through said electromagnet said switch device will be moved into the opposite direction, and a supplemental 10 rail composed of insulating material mov- ably mounted in connection with one of the current carrying rails of said track section, and said supplemental rail being in opera- tive connection with the means for actuating 15 said signal arm.

10. A block system for miniature electric railways comprising a plurality of electric signal post constructions located at predetermined points along the track of a railway 20 and provided with electric elements, the electric elements of said signal post constructions being in electrical connection with the current carrying rails of the railway track, and mechanical means in operative connec- 25 tion with said signal post constructions for automatically operating the signal elements thereof to move the same into danger positions in the progress of one or more electric locomotives or cars over the track of said 30 railway.

11. A block system for miniature electric railways comprising a plurality of electric signal post constructions located at predetermined points along the track of a railway 35 and provided with electric elements, the electric elements of said signal post constructions being in electrical connection with the current carrying rails of the railway track, mechanical means in operative connection 40 with said signal post constructions for automatically operating the signal elements thereof to move the same into danger positions in the progress of one or more electric locomotives or cars over the track of said 45 railway, and means involving rails composed of insulating material in operative connection 50 with said mechanical means for automatically stopping a locomotive or car as it approaches signal post constructions, the signal elements of which are set at danger.

12. A block system for miniature electric railways comprising a plurality of electric signal post constructions located at predetermined points along the track of a railway 55 and provided with electric elements, the electric elements of said signal post constructions being in electrical connection with the current carrying rails of the railway track, mechanical means in operative connection 60 with said signal post constructions for automatically operating the signal elements thereof to move the same into danger positions in the progress of one or more electric locomotives or cars over the track of said

railway, means involving rails composed of insulating material in operative connection with said mechanical means for automatically stopping a locomotive or car as it approaches signal post constructions, the signal elements of which are set at danger, and elec- 70 trical means for automatically moving said last named means into inoperative position to permit of the progress of said locomotive or car on said track.

13. A block system for miniature electric 75 railways comprising a plurality of electric signal post constructions located at predetermined points along the track of said railway and provided with electric elements, the electric elements of said signal post constructions being in electrical connection with the current carrying rails of the railway track, mechanical means in operative connection with said signal post constructions for automatically operating the signal elements 80 thereof to move the same into danger positions in the progress of one or more electric locomotives or cars over the track of said railway, means involving rails composed of insulating material in operative connection 85 with said mechanical means for automatically stopping a locomotive or car as it approaches signal post constructions, the signal elements of which are set at danger, elec- 90 trical means for automatically moving said last named means into inoperative position to permit of the progress of said locomotive or car on said track, and means involving a rail composed of insulating material for automatically stopping a locomotive or car 95 about to enter a switch construction in the track of said railway.

14. The combination with a miniature railway having current carrying rails and a locomotive or car having contact members 105 adapted to engage one of said current rails, of a block system comprising a plurality of electric signal post constructions located at predetermined points along the tracks of the railway and provided with electric elements, 110 the electric elements of said signal post constructions being in electrical connection with the carrying rails of the railway, and mechanical means in operative connection with said signal post constructions for automatically 115 operating the signal elements thereof to move the same into danger positions in the progress of one or more electric locomotives or cars over the track of said railway.

15. The combination with a miniature 120 railway having current carrying rails and a locomotive or car having contact members adapted to engage one of said current rails, of a block system comprising a plurality of electric signal post constructions located at 125 predetermined points along the tracks of the railway and provided with electric elements, the electric elements of said signal post con-

structions being in electrical connection with the carrying rails of the railway, mechanical means in operative connection with said signal post constructions for automatically 5 operating the signal elements thereof to move the same into danger positions in the progress of one or more electric locomotives or cars over the track of said railway, and means involving rails composed of insulating material in operative connection with 10 said mechanical means for automatically

stopping a locomotive or car as it approaches signal post constructions the signal elements of which are set at danger.

In testimony that I claim the foregoing as 15 my invention I have signed my name in presence of the subscribing witnesses this 20th day of January 1921.

AINSLEY L. JONES, 2d.
